METHOD OF AND APPARATUS FOR EMPLOYING TUNING FORKS TO GENERATE AUDIO FREQUENCY CURRENT AS A MEDIUM FOR SOUND

Application filed July 5, 1928. Serial No. 290,502.

This invention relates to new and useful improvements in sound reproducers and an improved method of sound reproduction.

One object of this invention is a new method of producing musical notes amplified in volume.

Another object of this invention is a suitable form of apparatus for carrying out the said method.

10 Another object of this invention is a "silent piano."

In accordance with this invention a tuning fork having a period of vibration corresponding to that of a predetermined musical note, and forming in conjunction with an electromagnet situated between its free ends a substantially closed magnetic circuit, is caused to vibrate to vary the reluctance of said magnetic circuit, whereby alternating current is generated in the coil of said electromagnet, the frequency and amplitude of said current being dependent upon the period of vibration of said tuning fork and characteristic of the desired musical note. The current thus generated is connected to the input circuit of an audio-frequency amplifier whose output circuit includes a suitable form of telephone or loud speaker, whereby the musical note corresponding to the period of vibration of said tuning fork, but many times amplified, is reproduced in said telephone or loud speaker.

In the drawings, comprising but a single sheet of two figures, one suitable form of apparatus for performing the several steps of the said method in their proper sequence is diagrammatically and schematically set forth.

40 Figure 1 is a schematic diagrammatic representation of a suitable form of apparatus for producing, translating, amplifying, and reproducing, a particular musical note; and

45 Figure 2 is a schematic representation of a simple form of musical instrument or appa-

ratus arranged to amplify and reproduce a plurality of different musical notes.

It should of course be understood that the devices of Figures 1 and 2 are merely illustrative and that the number of musical notes 50 which may be reproduced from an apparatus constructed in accordance with and embodying the principle of this invention is only limited by the number of musical notes which are audible to the human ear. One 55 commercial form of the invention would be an electro-mechanical piano having the scale commonly used in commercial pianos.

Referring to Figure 1, the hammer 11 at the right of the figure, which is pivoted at 14, is adapted to strike the tuning fork 3 under the control of the pivoted member 13, whenever the key 12 is depressed to actuate said member 13. It will be understood that after striking the tuning fork 3, the hammer 65 11 will return to its normal position under the influence of gravity or under control of a suitable retractile spring. The tuning fork 3 may be of any preferred form of magnetic substance, the tuning fork being magnetized. 70 The base of the tuning fork is secured as at 4 to a suitable foundation 5. An electromagnet 6 is positioned between the extremities of the prongs of the tuning fork 3 and is so adjusted with respect to said prongs that the 75 core 7 of the electromagnet 6 affords sufficient clearance with respect to the prongs of the tuning fork 3 to permit the said prongs to freely vibrate and emit the musical note characteristic of the period of vibration of 80 said tuning fork 3. The vibratory movement of the prongs of said tuning fork 3 causes the air gaps between the polar faces of the core 7 and the prongs of the tuning fork 3 to be varied whereby the reluctance of the magnet 85 circuit formed by the said tuning fork and the core piece 7 is caused to vary, thereby generating an alternating current in the winding of the electromagnet 6. The amplitude and frequency of the current thus gen- 90

erated in the winding will depend upon the period of vibration of the tuning fork, which, in turn, as is well known, depends upon the period of vibration of the desired note. The winding of the electromagnet 6 forms a part of the input circuit of an amplifier. In the embodiment disclosed in the drawing the winding of the electromagnet 6 is connected in inductive relation with the input circuit 5 of the amplifier by means of a transformer 8 whose primary winding 9 is in series with the winding of the electromagnet 6, and whose secondary winding 10 is connected to the grid 23 of the thermionic tube 20. The filament 10 of said tube is connected in series with a suitable battery 25 and a rheostat 24. A suitable telephone or loud speaker is connected by means of a plug and jack to the output circuit of said amplifier, said circuit including the plate 22 of the thermionic tube 20. It thus appears that when the key 12 is depressed the hammer 11 will strike the prong 15 of the tuning fork 3 and cause said tuning fork to vibrate in accordance with its period 20 of vibration, which will correspond to the period of vibration of a particular musical note. The tuning fork, by varying the reluctance of the magnetic circuit, including the core 7 of the electromagnet 6, will generate 25 an alternating current in the winding of said electromagnet having a frequency and amplitude depending upon the period of vibration of the tuning fork 3. This current may be amplified through as many stages of audio-frequency amplification as may be desirable 30 before being impressed upon the circuit of an electromagnetic sound-reproducing unit.

Figure 2 is a modification of the device of Figure 1 schematically illustrative of one embodiment of the invention as applied to a device for producing a plurality of different musical notes. In Figure 2 the hammers 11 and 50 to 52 and the associated tuning forks 3 and 60 to 62 and electromagnets 6 and 30 to 32 are shown in plan. It should be understood however, that the number of tuning forks and associated mechanism may be increased or decreased depending upon the musical scale desired. The transformer 8 is also modified and is provided with a secondary winding 10 and with a plurality of primary windings 9, 40, 41 and 42, each of the said primary windings being in circuit with the winding of its associated electromagnet irrespective of the particular apparatus employed; the windings of the several electromagnets are connected to the input circuit of one or more audio-frequency amplifiers, and a suitable telephone or loud speaker common 55 to the device forms a part of the output circuit of the amplifier system.

It thus appears that whenever one of the hammers strikes one of the tuning forks the telephone receiver or loud speaker will cause 60 a musical note corresponding to the musical

note peculiar to the said tuning fork but greatly increased in volume, to be emitted, and the notes thus emitted will change as frequently as the operator depresses a different key. It thus appears that the principle of the apparatus illustrated herein may be embodied in any suitable form of musical instrument, such for example, as a piano, and the equipment required in a piano embodying the principle of this invention may be housed 70 within a much smaller housing than the strings of the ordinary commercial piano. Furthermore, when an ordinary headgear receiver is substituted for the loud speaker, a piano constructed in accordance with the principle of the present invention may be operated without causing inconvenience to other people, because the only person who would be able to hear the music which is produced would be the individual listening in the telephone receiver. It therefore appears that a piano embodying the principle of this invention has an advantage not possessed by the present commercial product in that it may be transformed into a "silent piano" if 80 so desired.

Of course it will be understood that the magnetized tuning fork is in reality a tuned, magnetized reed, and other forms of magnetized, tuned reeds might be used instead of a magnetized tuning fork, without departing from the spirit of the invention. Similarly, the core of the electromagnet may be a permanent magnet, in which event the tuned reed may or may not be magnetized, as preferred.

What is claimed is:

1. The method of producing a musical note which consists in vibrating a magnetized tuning fork whose period of vibration corresponds to the period of vibration of the desired note to vary the reluctance of a magnetic circuit including said tuning fork and the core of an electromagnet thereby generating an electric current in the winding of said magnet, the frequency and amplitude of said current being dependent upon the period of vibration of the tuning fork, in amplifying the current thus generated, and in applying the current thus amplified to the terminals of the winding of an electro-mechanical sound reproducer to reproduce the musical note emitted by the tuning fork.

2. In a musical instrument a magnetized tuning fork, an electromagnet positioned in spaced relation between the prongs of said fork, means operable to vibrate said tuning fork to generate a current in the winding of said electromagnet, means for amplifying the current, an electro-mechanical sound reproducer, and a circuit including the winding of said reproducer and the output circuit of said amplifier.

3. In a musical instrument a plurality of magnetized tuning forks, a plurality of elec-

tromagnets, a substantially closed magnetic circuit for each tuning fork, said magnetic circuit including said tuning fork and the core of one of said electromagnets, means selectively operable to vibrate any particular tuning fork to generate a current in the winding of the electromagnet associated therewith, means for amplifying the current thus generated, an electro-mechanical sound reproducer, and a circuit including the winding of said reproducer and the output circuit of said amplifier.

Signed at Port Jefferson, in the county of Suffolk and State of New York this 29th day of June, A. D. 1928.

MAX SCHUMM.
